WITNESSES:

Emily S. Graver

Schenck's Erdgaz

Fig. 1
55

The drawing shows a cross-sectional view of a mechanical assembly. It features a central vertical rod with a flared top and bottom. A spring (50) is wound around the top of the rod. A small rectangular component (51) is positioned above the spring. The rod passes through a cylindrical housing. Inside the housing, there are several horizontal plates or washers. The bottom of the rod is supported by a base plate (34) which is secured to a larger structure (35). The side walls of the housing are labeled with dimensions: 36, 38, 39, and 48. The top of the rod is labeled with 46 and 30. The side of the housing is labeled with 37. The title block in the top left corner contains 'Fig. 1' and '55'.

2 SHEETS—SHEET 2.

UNITED STATES PATENT OFFICE.

ROBERT J. COPELAND AND ALBERT E. CHATTERSON, OF TORONTO, ONTARIO, CANADA.

BINDER.

No. 867,706.

Specification of Letters Patent.

Patented Oct. 8, 1907.

Application filed January 21, 1905. Serial No. 242,058.

To all whom it may concern:

Be it known that we, ROBERT J. COPELAND, a citizen of the United States, and ALBERT E. CHATTERSON, a subject of the King of Great Britain, and both residents of Toronto, Dominion of Canada, and whose post-office address is No. 75 Queen street, West, in said city, have invented certain new and useful Improvements in Binders, of which the following is a specification.

This invention relates to binders and more particularly such as are designed for use as loose-leaf ledgers.

The invention relates more especially to the locking devices and consists of the features hereinafter set forth.

In the accompanying drawings forming part of this specification the various features of the invention are illustrated in their preferred form, like reference numerals designating corresponding parts in the various figures.

Figure 1 is a front elevation of the binder showing the upper and lower strips thereof separated to the limit, 20 one cover being removed and the other cover being partly broken away. Fig. 2 is a horizontal section taken on line 2—2 of Fig. 1 and showing a portion of one of the sheets in dotted lines. Fig. 3 is a vertical section taken on line 3—3 of Fig. 1. Fig. 4 is a vertical 25 section through line 4—4 of Fig. 3. Fig. 5 is a plan view of part of the upper strip of the binder. Fig. 6 is a vertical section through line 6—6 of Fig. 1. Fig. 7 is a bottom plan view of the key plate and attached parts associated with the removable post. Fig. 8 is an elevation partly in section showing a detail of the binder lock.

Referring now to the specific construction and arrangement of the various features as shown in the drawings; 1 and 2 are the upper and lower strips of the 35 binder between which the sheets 3 are secured. These sheets have open holes, 4, 5, 6, and 7 which respectively, engage the posts 8, 9, 10, and 11. These posts are extensible and have their opposite ends fixed to the opposite strips as shown. The covers such as 12 and 40 13 are hinged to the upper and lower strips. These strips 1 and 2 are L-shaped in cross section and the space between the rear portions of these strips is covered by a back 14.

15 and 16 are two extensible posts fixed to the upper 45 and lower strips and each containing an internal spring such as 17, said springs operating to press the strips apart. The back 14 is held in position with reference to these strips by certain extensible connections, now to be described.

50 The back is made of sheet metal and is provided with tubular guides 18, 19, 20 and 21.

22 is a rod or block which slides in the guides 18 and

19 and carries the joint of a toggle. This toggle consists of the cross piece 23, fixed to the block 22, and the arms 24 and 25 pivoted to the cross piece 23 and to the upper 55 and lower strips of the binder.

26 is the block or rod similar to the block 22 and sliding in the guides 20 and 21. This block carries a toggle whose parts 27, 28 and 29 are similar in arrangement and connection to the toggle 23, 24, and 25. The upper 60 and lower binding strips are preferably made of cast metal.

30 is the lock casing cast on the upper binding strip. This lock casing is formed with two channels 31 and 32, in which work the rack posts 33 and 34 fixed to the 65 lower strip 2.

35 and 36 are two gears carried on the lock casing and which mesh with each other and also with the rack posts 33 and 34, respectively.

37 is a reciprocating latch provided with a finger or 70 detent 38 arranged to engage the teeth of both gears. This latch is provided with a cam 39 at its upper end and is held in place by the block 40 secured to the lock casing and having a recess to receive the latch; one wall of this recess is shown by dotted lines on Fig. 8.

41 is a spring whose lower end engages the detent 38 and tends to hold the latch in its upper position with the detent 38 in engagement with the teeth of the gears 35 and 36. The upper end of the spring 41 is held in place by the block 40.

42 is a rotatable piece, the lower end of which rests in a bearing in the block 40 and the upper end of which extends into an opening in the upper strip. The upper end of this piece 42 is adapted to receive and be rotated by a key 43 which enters a key-hole in the upper 85 strip. This rotatable piece 42 carries a pin 44 designed to engage the cam 39 of the latch 37 and thereby move the latch downward against the spring 41 so as to disengage the detent 38 from the gears 35 and 36 and thereby unlock the binder.

45 is a pin on the latch 37 which works in a recess 46 on the back of the lock casing 30 and limits the downward movement of the latch and thus prevents the pin 44 from being turned so far as to run off the cam 39.

The sheets 3 are provided with closed holes 47 which 95 engage a removable post 48 extending between the strips and through an aperture 49 in the upper strip. The post 48 is extensible and contains an internal spring 50 which tends to extend the post. In the head of the post 48 is a groove 51, the purpose of which will 100 be presently explained.

52 is an escutcheon which is secured to the upper strip 1. This escutcheon 52 is made of two thin metal plates 53 and 54 secured together so as to leave a shallow

- space between them. In this space slides the reciprocating plate 55 adapted to enter the groove 51 of the removable post 48, when the latter is in position, and lock the post in place.
- 5 56 is a spring, one end of which is secured to the under side of the plate 54, and the other end of which projects through an opening 57 in this plate and is secured to the pin 58 on the plate 55. The spring 56 tends to retract the plate 55 and thereby disengage it from the post 48.
- 10 59 is a spring, one end of which is secured on the under side of the plate 54. This spring passes near the key-hole of the escutcheon and has its free end bent over to engage with a finger 60 on the plate 55. When the key 43 is entered in the latch and turned, it rotates
- 15 the piece 42 thereby disengaging the latch 37 from the gears 35 and 36. In moving the key also presses against the spring 59 thereby disengaging its free end from the finger 60 of the plate 55. The spring 56 thereupon retracts the plate 55 as far as the key will permit, and
- 20 when the key is withdrawn the plate 55 is retracted all the way back. This releases the post 48 so that sheets may be withdrawn from or inserted in the binder. When the removable post 48 is re-inserted the plate 55 is drawn forward by pressing against the lip 69 which
- 25 projects through the opening 70 in the escutcheon plate 53 so as to engage the groove 51 of said post. When the plate 55 has been drawn forward the finger 60 is again engaged by the spring 59 so that said plate is again locked in this position and the removable post locked
- 30 in place.
- 68 is a small coiled spring in the block 40 acting to press upward the rotatable piece 42 and thus prevent the latter from rotating by sudden jar and forcing the latch 37 downward and so unlock the binder.
- 35 It will be understood of course that when the binder is unlocked the springs 17 move the strips 1 and 2 apart and that during this movement the removable post 48 is extended by its spring 50. It will also be observed that the latch 37 of the binder lock acts to prevent the
- 40 backward rotation of the gears 35 and 36. That is to say, it prevents the rotation of these gears in that direction in which they must move when the strips separate. The rotation of the gears in the opposite or forward direction is not prevented by the latch 37, a tooth of first
- 45 one gear and then the tooth of the other gear pressing the detent 38 of the latch downward out of the way against the spring 41. Thus after the binder has been unlocked and the strips 1 and 2 separated the key may be withdrawn. The strips may thereafter be pressed together as far as desired without operating the lock of the binder by the key. As the strips are moved together they are automatically locked against separation at every stage of their approach toward each other. It will also be observed that by the employment of a rack
- 50 post carried by one strip and a gear meshing therewith and carried by the other strip and associated with means to prevent the backward rotation of the gear, a strong, durable lock is provided.
- While it is preferred to employ two gears meshing
- 55 with two rack posts as above set forth and while it is preferred to have these two gears mesh with each other, as described, these two latter features may be omitted without departing from the scope of the invention.

Moreover, the invention is not to be limited to the precise form or arrangement of the various parts as shown 65 in the drawings. These may be variously modified or combined without departing from the scope of the invention.

1. In a binder, the combination of upper and lower strips movable to and from each other; a rack post carried by 70 one strip; a gear carried by the other strip meshing with said rack post and rotatable by said rack post in a forward direction when the strips are pressed towards each other; and means for automatically locking each tooth of the gear against backward rotation at each step of its forward rotation. 75

2. In a binder, the combination of upper and lower strips movable to and from each other; a rack post carried by one strip; a gear meshing with said rack post and carried by the other strip; and key operated means automatically 80 engaging the gear at each step of its forward rotation for locking the gear against backward rotation whereby when the gear is locked the strips are locked against separation.

3. In a binder, the combination of upper and lower strips; movable to and from each other; a rack post carried by one strip; a gear meshing with said rack post and carried by the other strip; and a key operated spring latch automatically engaging the gear at each step of its forward rotation for locking the gear against backward rotation. 85

4. In a binder, the combination of upper and lower strips movable to and from each other; a rack post carried by one strip; a gear meshing with said rack post and carried by the other strip; and rotatable by said rack post in a forward direction when the strips are pressed toward each other and a reciprocating key operated latch automatically 90 engaging the gear at each step of its forward rotation for locking the gear against backward rotation. 95

5. In a binder, the combination of upper and lower strips movable to and from each other; a rack post carried by one strip; a gear meshing with said rack post and carried by the other strip; a latch automatically engaging the gear at each step of its forward rotation for locking the gear against backward rotation, said latch having a cam; and a key rotated piece to engage said cam and operate the latch. 100

6. In a binder, the combination of upper and lower strips movable to and from each other; a rack post carried by one strip; a gear meshing with said rack post and carried by the other strip; a reciprocating spring latch automatically engaging the gear at each step of its forward rotation for locking the gear against backward rotation, said latch having a cam; and a key rotated piece to engage said cam and operate the latch. 110

7. In a binder, the combination of upper and lower strips movable to and from each other; two racks carried by one strip; two gears carried by the other strip and meshing each with a rack; and a latch to engage the teeth of both gears and thereby lock them against backward rotation. 115

8. In a binder, the combination of upper and lower strips movable to and from each other; two racks carried by one strip; two gears carried by the other strip and meshing together and also each with a rack; and a latch to engage the teeth of both gears and thereby lock them against backward rotation. 120

9. In a binder, the combination of upper and lower strips movable to and from each other; two racks carried by one strip; two gears carried by the other strip and meshing each with a rack; and a reciprocating key operated spring latch to engage the teeth of both gears and thereby lock them against backward rotation. 125

10. In a binder, the combination of upper and lower strips movable to and from each other; two racks carried by one strip; two gears carried by the other strip and meshing each with a rack; a reciprocating latch to engage the teeth of both gears and thereby lock them against backward rotation, said latch having a cam; and a key rotated piece to engage said cam and operate the latch. 130

11. In a binder the combination of upper and lower strips movable to and from each other; two racks carried

- by one strip; two gears carried by the other strip and meshing together and also each with a rack; a reciprocating latch to engage the teeth of both gears and thereby lock them against backward rotation, said latch having a 5 cam; and a key rotated piece to engage said cam and operate the latch.
12. In a binder, the combination of upper and lower strips; a lock for the binder; a removable post extending between the strips and through the upper strip; and a 10 plate carried by the upper strip arranged to engage and release said post, said plate being mechanically separate and disconnected from the binder lock and independently operable.
13. In a binder, the combination of upper and lower strips; a lock for the binder; a removable post extending between the strips and through the upper strip; and a reciprocating plate carried by the upper strip arranged to engage and release said post, said plate being mechanically 15 separate and disconnected from the binder lock and independently operable.
14. In a binder, the combination of upper and lower strips; a lock for the binder; a removable post extending between the strips and through the upper strip; and a plate carried by the upper strip arranged to engage and release said post, said plate being mechanically disconnected from the binder lock; and a key operated latch for said plate.
15. In a binder the combination of upper and lower strips; a lock for the binder; a removable post extending between the strips and through the upper strip; and a spring retracted reciprocating plate carried by the upper strip and arranged to engage and release said post, said plate being mechanically disconnected from the binder lock.
- 35 16. In a binder, the combination of upper and lower strips; a lock for the binder; a removable post extending between the strips and through the upper strip; and a spring retracted reciprocating plate carried by the upper strip arranged to engage and release said post, said plate being mechanically disconnected from the binder lock; and a key operated latch for said plate.
17. In a binder the combination of upper and lower strips movable to and from each other; a rack post carried by one strip; a gear carried by the other strip meshing with said rack post and rotatable in a forward direction when the strips are pressed towards each other; a reciprocating spring latch to engage the teeth of said gear and prevent its rotation in a backward direction; said latch having a cam; and a key operated and axially mounted cylindrical cam piece provided with a projecting pin to engage said cam and operate said latch.
- 45 18. In a binder the combination of upper and lower strips movable to and from each other; two rack posts carried by one strip; two gears carried by the other strip each meshing with a separate rack post and rotatable in a forward direction when the strips are pressed towards each other; a reciprocating spring latch to engage the teeth of said gears and prevent their rotation in a backward direction; said latch having a cam; and a key operated and axially mounted cylindrical cam piece provided with a projecting pin to engage said cam and operate said latch.
- 50 19. In a binder the combination of upper and lower strips movable to and from each other; two rack posts carried by one strip; two gears carried by the other strip meshing together and each meshing with a separate rack post and rotatable in a forward direction when the strips are pressed towards each other; a reciprocating spring latch to engage the teeth of said gears and prevent their rotation in a backward direction; said latch having a cam; and a key operated and axially mounted cylindrical cam piece provided with a projecting pin to engage said cam and operate said latch.
- 55 20. In a binder the combination of upper and lower strips movable to and from each other; a rack post carried by one strip; a gear carried by the other strip meshing with said rack post and rotatable in a forward direction when the strips are pressed towards each other; a reciprocating spring latch to engage the teeth of said gear and prevent its rotation in a backward direction; said latch having a cam; and a key operated and axially mounted cylindrical cam piece provided with a projecting pin to engage said cam and operate said latch.
- 60 21. In a binder the combination of upper and lower strips movable to and from each other; two rack posts carried by one strip; two gears carried by the other strip each meshing with a separate rack post and rotatable in a forward direction when the strips are pressed towards each other; a reciprocating spring latch to engage the teeth of said gears and prevent their rotation in a backward direction; said latch having a cam; a key operated and axially mounted cylindrical cam piece provided with a projecting pin to engage said cam and operate said latch, said cam piece mounted on one strip approximately parallel with said rack post and terminating adjacent the inner face of said strip; and said strip being provided with a key hole in alignment with said cam piece.
- 65 22. In a binder the combination of upper and lower strips movable to and from each other; two rack posts carried by one strip; two gears carried by the other strip each meshing with a separate rack post and rotatable in a forward direction when the strips are pressed towards each other; a reciprocating spring latch to engage the teeth of said gears and prevent their rotation in a backward direction; said latch having a cam; a key operated and axially mounted cylindrical cam piece provided with a projecting pin to engage said cam and operate said latch, said cam piece mounted on one strip approximately parallel with said rack posts and terminating adjacent the inner face of said strip; and said strip being provided with a key hole in alignment with said cam piece.
- 70 23. In a binder the combination of upper and lower strips movable to and from each other; a rack post carried by one strip; a gear carried by the other strip meshing with said rack post and rotatable in a forward direction when the strips are pressed towards each other; a reciprocating spring latch to engage the teeth of said gear and prevent its rotation in a backward direction; said latch having a cam; a key operated and axially mounted cylindrical cam piece provided with a projecting pin to engage said cam and operate said latch, said cam piece mounted on one strip approximately parallel with said rack posts and terminating adjacent the inner face of said strip; and said strip being provided with a key hole in alignment with said cam piece.
- 75 24. In a binder the combination of upper and lower strips movable to and from each other; two rack posts carried by one strip; two gears carried by the other strip meshing together and each meshing with a separate rack post and rotatable in a forward direction when the strips are pressed towards each other; a reciprocating spring latch to engage the teeth of said gears and prevent their rotation in a backward direction; said latch having a cam; and a key operated and axially mounted cylindrical cam piece provided with a projecting pin to engage said cam and operate said latch; said cam piece mounted on the strip carrying the gear and terminating adjacent the inner face of said strip; and said strip being provided with a key hole in alignment with said cam piece.
- 80 25. In a binder the combination of upper and lower strips movable to and from each other; a rack post carried by one strip; a gear carried by the other strip meshing with said rack post and rotatable in a forward direction when the strips are pressed towards each other; a reciprocating spring latch to engage the teeth of said gear and prevent its rotation in a backward direction; said latch having a cam; and a key operated and axially mounted cylindrical cam piece provided with a projecting pin to engage said cam and operate said latch, said cam piece mounted on one strip approximately parallel with said rack post and terminating adjacent the inner face of said strip.

said strip; a thrust spring bearing against the inner end of said cam piece to retard its rotation; and said strip being provided with a key hole in alinement with said cam piece.

5 26. In a binder the combination of upper and lower strips movable to and from each other; two rack posts carried by one strip; two gears carried by the other strip meshing together and each meshing with a separate rack post and rotatable in a forward direction when the strips 10 are pressed towards each other; a reciprocating spring latch to engage the teeth of said gears and prevent their rotation in a backward direction; said latch having a cam; and a key operated and axially mounted cylindrical cam piece provided with a projecting pin to engage said

cam and operate said latch; said cam piece mounted on 15 the strip carrying the gears approximately parallel with the said rack-posts and terminating adjacent the inner face of said strip; a thrust spring bearing against the inner end of said cam piece to retard its rotation; and said strip being provided with a key hole in alinement 20 with said cam piece.

In testimony whereof, we have signed our names to this specification, in the presence of two subscribing witnesses.

ROBERT J. COPELAND.
ALBERT E. CHATTERSON.
